UNITED STATES PATENT OFFICE

109,508

DESIGN FOR A SAUCER

Gisela Wood, San Francisco, Calif.

Application April 24, 1937, Serial No. 68,964

Term of patent 7 years

To all whom it may concern:

Be it known that I, Gisela Wood, a citizen of the United States, residing in the city and county of San Francisco, and State of California, have invented a new, original, and ornamental Design for a Saucer, of which the following is a specification, reference being had to the accompanying drawing, forming part thereof, in which

I claim:

The ornamental design for a saucer, substantially as shown.

GISELA WOOD.
